UNITED STATES PATENT OFFICE

96,251

DESIGN FOR A SHOE

Arent Heil, Upper Darby, Pa., assignor to Laird Schober & Company, Philadelphia, Pa., a firm comprising George S. Laird, Samuel S. Laird and J. Laird Schober

Application May 31, 1935, Serial No. 57,083

Term of patent 3½ years

To all whom it may concern:

Be it known that I, Arent Heil, a citizen of the United States, residing in Upper Darby, Delaware County, Pennsylvania, have invented a new, original, and ornamental Design for a Shoe, of which the following is a specification, reference being had to the accompanying drawing, forming a part thereof, in which

Fig. 1 is a plan view of a shoe showing my new design; and

Fig. 2 is a side elevation thereof.

I claim:—

The ornamental design for a shoe, substantially as shown.

ARENT HEIL.
